FREELAND W. OSTROM, OF NEWARK, NEW JERSEY.

OVERSHOE.

1,169,562.

Specification of Letters Patent.

Patented Jan. 25, 1916.

Application filed January 17, 1911. Serial No. 603,135.

To all whom it may concern:

Be it known that I, FREELAND W. OSTROM, a citizen of the United States, residing at Newark, in the county of Essex and State of New Jersey, have invented a certain new and useful Improvement in Overshoes, of which the following is a full, clear, and exact description.

This invention relates to improvements in overshoes, particularly of the water-proof variety, and has for its object to provide means for securely holding the so-termed "low" overshoes and the comparatively loosely-fitting "high" overshoes in heel fitting position with respect to the inner shoe.

It is common knowledge that in practical use a low overshoe, unless closely fitting the inner shoe, is liable to accidental displacement, and it is a common occurrence for the heels of loosely fitting overshoes of medium or ordinary height to move up and down on the heel of the inner shoe during the act of walking, thus causing a friction which is not only annoying to the wearer but destructive to both the inner and outer shoes. It is also well understood that it is a comparatively difficult undertaking for obese, rheumatic and aged persons, and those of feeble health, to draw on a snugly-fitting overshoe of the class commercially termed "storm overshoes."

To overcome the difficulties incident to the wearing of the first and second mentioned varieties and to lessen the difficulty incident to putting on the last mentioned style of overshoe are the primary objects of this invention, and to this end the overshoe is provided with a yielding resistance member which is acted upon by the toe of the inner shoe to hold the outer or over shoe in heel fitting position with respect to the inner shoe, thus making it practical to wear comparatively loosely fitting overshoes without the annoyance of accidental displacement and looseness at the heel, and lessening the difficulty of drawing on the extra high or storm variety.

In the accompanying drawings illustrating the invention, in the several figures of which like parts are similarly designated, Figure 1 is a view in side elevation of an inner shoe fitted with an outer or over shoe, the latter being equipped with the present invention and broken out at its forward end to better illustrate its application. Fig. 2

is a dotted line view, in perspective, of the overshoe shown in Fig. 1, illustrating in full lines the yielding resistance member. Fig. 3 is a view on a larger scale illustrating the character of the yielding resistance member shown in the previous figures. Fig. 4 is a perspective view of the overshoe shown in Figs. 1 and 2, illustrating the yielding resistance member secured to the overshoe in a position transverse to that shown in Figs. 1 and 2.

Referring to the drawings, 1 represents the outer or over shoe, 2 the inner shoe and 3 the yielding resistance member comprising the elastic portion 4 and non-elastic web ends 5 and 6. In the present embodiment of the invention, the web ends 5 and 6 are glued to the underside of the upper toe portion 7 and the upper side of the innersole 8, respectively, but it is to be understood that upon the character of the yielding resistance member employed depends the character of the means employed for securing such member. As shown in Figs. 1 and 2, the resistance member is secured in the overshoe in a position to cause the upper portion of the toe of the inner shoe, when positioned as shown in Fig. 1, to expand the elastic portion 4 of the yielding resistance member.

In Fig. 4, the yielding resistance member is shown as lying in a plane transverse to that shown in Figs. 1 and 2, whereby said member is brought into yielding contact with the rounded portion 9 of the sole of the inner shoe.

While the construction and application of the yielding resistance member herein shown and described is believed to constitute an extremely desirable means and method, it is within the invention to employ any yielding member so positioned as to cause the outer shoe to be held in heel fitting position with respect to the inner shoe, through its action on the toe of said inner shoe in accordance with the following claims. It is also to be said that the material of the yielding or resistance member may be and preferably is nonmetallic, but in any case it is of such character as not to abrade, or otherwise injuriously affect either the inner shoe or the overshoe itself; and furthermore, this member is of such small bulk that it may be fitted in the toe of the overshoe either lengthwise or crosswise and yet permit of its use in the overshoe without involving the use of an

overshoe of larger size. In other words, an overshoe of given size may be used on a given size inner shoe for which it is designed, whether the resistance member is 5 present or absent. For example, a wearer using a number 8 overshoe may use that size when the resistance member is employed.

Claims:—

1. An overshoe, having a yielding resistance member comprising a strip of non-abrading elastic material arranged in its toe portion and secured by its opposite ends to said toe portion and having its intermediate portion free to yield under pressure of the 10 toe of an inner shoe in the act of applying the overshoe to such inner shoe and thereby draw the heel portion of the overshoe into fitting position on the inner shoe and hold the overshoe against accidental displacement 15 with respect to the inner shoe and adapted for use without requiring a larger size overshoe than one normally required for an inner shoe of given size.
2. An overshoe, provided with a resistance 20 member consisting of a strip of elastic material arranged lengthwise in the toe portion of the overshoe, and having one end secured to the upper of the overshoe and its other end secured to the sole and its intermediate 25 part free, so that when acted on by an inner shoe it yieldingly holds said overshoe against accidental displacement with respect to the inner shoe.
3. An overshoe, provided with a resistance 30 member consisting of a strip of non-metallic elastic material having non-elastic end sections, said strip secured by its non-elastic end sections in the toe portion of the overshoe with the elastic portion free to respond 35 to pressure when acted upon by an inner shoe in the act of applying the overshoe to such inner shoe and serving to draw the heel portion of the overshoe into fitting position on 40

the inner shoe and hold the overshoe against accidental displacement with respect to the 45 inner shoe.

4. An overshoe, provided with a resistance member consisting of a strip of elastic material arranged lengthwise of the overshoe in its toe portion and provided with non- 50 elastic ends one of which is secured to the upper and the other to the sole, the intermediate elastic part being free to respond by the inner shoe to hold the overshoe thereon against accidental displacement. 55

5. An overshoe, having secured inside its toe portion a yielding resistance member of little bulk and of a material that will conform to the contour of the toe portion of the inner shoe as the overshoe is fitted to such 60 inner shoe and adapted for use without requiring a larger size overshoe on an inner shoe of given size and free to yield toward the overshoe toe when engaged by the toe of the inner shoe, whereby the heel portion of 65 the overshoe is snugly seated upon the heel portion of the inner shoe.

6. An overshoe, provided with a resistance member consisting of non-metallic elastic material secured in the toe portion of the 70 overshoe and free to respond to pressure when acted upon by an inner shoe in the act of applying the overshoe to such inner shoe and serving to draw the heel portion of the overshoe into fitting position on the inner 75 shoe and hold the overshoe against accidental displacement with respect to the inner shoe.

In testimony whereof I have hereunto set my hand this 16th day of January, A. D. 80 1911.

FREELAND W. OSTROM.

THOMAS CAMPBELL,

ABbie M. DONIHEE.

Copies of this patent may be obtained for five cents each, by addressing the "Commissioner of Patents, Washington, D. C."

It is hereby certified that in Letters Patent No. 1,169,562, granted January 25, 1916, upon the application of Freeland W. Ostrom, of Newark, New Jersey, for an improvement in "Overshoes," an error appears in the printed specification requiring correction as follows: Page 2, line 53, claim 4, after the word "respond" insert the words *to pressure*; and that the said Letters Patent should be read with this correction therein that the same may conform to the record of the case in the Patent Office.

Signed and sealed this 8th day of February, A. D., 1916.

[SEAL.]

R. F. WHITEHEAD,

Acting Commissioner of Patents.
